UNITED STATES PATENT OFFICE.

NAPOLEON B. ALLEN, OF NEW HYDE PARK, NEW YORK.

HINGE FOR CURTAIN STRETCHERS.

Application filed March 14, 1922. Serial No. 543,736.

To all whom it may concern:

Be it known that I, NAPOLEON BONAPARTE ALLEN, a citizen of the United States, and a resident of New Hyde Park, county of Nassau, State of New York, have invented certain new and useful Improvements in Hinges for Curtain Stretchers, of which the following is a full, clear, and exact description.

Among the principal objects which the present invention has in view are: To produce a joint of the character mentioned without increasing the bulk of the joined members; to form a rigid connection for end-butted coextensive members; to effect the joint quickly; and to simplify and cheapen the construction.

Drawings.

Figure 1 is a side view of a joint constructed and arranged in accordance with the present invention, the parts being shown by full lines in their closed or active relation and by dotted lines in their open or inactive relation;

Figure 2 is a side view taken from the side of the members opposite to that shown in the previous figure;

Figure 3 is a top edge view of the members shown in Figure 1; and

Figure 4 is a top edge view of the members as shown in Figure 2 of the drawings.

Description.

The present invention is adapted for various employment but is particularly adapted for use in conjunction with lace curtain stretcher frames, being there employed for connecting the sections of the elongated side members of the frame. It is in this connection the invention is illustrated in the accompanying drawings, wherein the two sections are indicated by the numerals 9 and 10. These sections are preferably grooved at their inner edge to form the under-cut edge 11, which is usually provided with necessary pins for threading the curtain upon.

As is well known, the elongated side members of the frame are preferably formed from a plurality of sections which are either separated and packed for storage or hinge-connected so that they may be released and disposed for storage.

The hinge employed in the present invention consists principally of the hinge butts

12 and 13. The butts 12 and 13 have hinge knuckle lugs 14 and 15 respectively. As best seen in Figure 4 of the drawings, the portion of the butt 13 bearing the lug 15 is offset a distance equal to the thickness of the lugs 60 14. The lugs are pivotally united by the hinge pin 16, the center of which is disposed in line with the ends of the liner brackets 17 with which the said butts are each provided. The liner brackets 17 serve to engage one 65 edge of each of the members 9 and 10 and true the disposition of the butts 12 and 13 thereon. This construction renders the operation of setting the butts on the sections 9 and 10 simply and easily accomplished, all 70 that is necessary being to rest the overturned ends of the brackets 17 on the edge of the said sections before the fastening screws 18 are driven.

It will be noted that the butt 13 and the 75 portion thereof carrying the lug 15 overlaps the end of the butt 12 with the result that the parting edges of the joined butts are on a plane offset from the plane coincident with the center of the pin 16. This is best shown in Figure 1 of the drawings. This arrangement allows the latch 19 to draw the ends of the sections 9 and 10 more rigidly together in the portions thereof juxtaposed to the pin 16.

The latch 19 is pivoted by means of the pin 20 to the over-hanging abutment 21 on the butt 13. When the latch is swung to the position shown in Figures 1 to 3 the body of the latch extends under the abutment 22. The latch 19 has an up-raised foot 23, that 90 is formed to bear against and to ride over the wedging edge 24 of the abutment 22. This is shown best in Figures 1 and 3 of the drawings.

Due to the inclined surface of the edge of the abutment 22 the latch 19 is permitted to exert a wedging pressure on the abutment 22 to force the same against the abutment 21.

The latch 19 is preferably provided with a handle 25 by which the said latch may be swung to the active and the inactive positions thereof disclosed in the drawings.

It is obvious that the butts 12 and 13 are 105 so simple of form and construction as to admit of being stamped or otherwise quickly produced from light or cast metal. It is also obvious that the hand work incident to the construction of the hinge joints being 110

limited as it is to the mounting of the pins 16 and 20, is reduced to a very small factor. It is also obvious that when the latch 19 is moved to its active position the strain exerted to part the sections 9 and 10 or to open the joint between the same, is counteracted by the resistance of the foot 23 and the edge 24 of the butt 22 and by the portion thereof which is perpendicular to the long axis of the sections 9 and 10 or parallel with the axis of the hinge pin 16. A simple, inexpensive and rigid hinge joint is thus produced.

Claims.

15. 1. An article as characterized comprising a plurality of hinge butts pivotally connected at approximately the termination of the meeting edges of said butts and having abutment members adjacent the opposite extremity of said meeting edges, said abutment members being extended from said butts in approximately perpendicular relation thereto; a latch pivotally mounted on one of said abutments for engaging the other of said abutments to draw said abutments together; and a plurality of liner brackets extending from the edge of said butts in substantially perpendicular relation thereto, said liner brackets being relatively disposed

in lines perpendicular to the meeting edges 30 of said butts.

2. An article as characterized comprising a plurality of elongated flat thin hinge butts the meeting portions whereof over-lap to form hinge lugs extending below the body 35 of said butts; a plurality of abutment brackets integrally formed on said butts adjacent the meeting edges thereof and extended therefrom in substantially perpendicular relation thereto, the edge of one of 40 said abutment brackets being inclined from the outer edge toward the body of the butt with which it is connected; a plurality of liner brackets integrally formed on said butts and extended therefrom to a plane 45 parallel with the center of said butts and perpendicular to the meeting edges thereof, said liner brackets being bent to a plane co-extensive in all of said brackets and perpendicular to the plane of said butts; and a latch connected to one of said abutment brackets to swing between the said abutment bracket and the article with which said butt is associated, said latch having an upset 50 head integrally formed with said latch for engaging the other of said brackets to ride over the inclined edge thereof.

NAPOLEON B. ALLEN.
